(57) **CLAIM**

The ornamental design for a parallel plane structure for cable railing terminals, as shown and described.

DESCRIPTION

FIG. 1 is a bottom perspective view of a parallel plane structure for cable railing terminals showing my new design; FIG. 2 is a front view thereof;

FIG. 3 is a rear view thereof;

FIG. 4 is a right side view thereof;

FIG. 5 is a left side view thereof;

FIG. 6 is a bottom view thereof; and,

FIG. 7 is a top view thereof.

The broken lines depict portions of the parallel plane structure for cable railing terminals in which the design is embodied that form no part of the claimed design.

The dot-dash-dot broken lines indicate a symbolic break in length. The appearance of any portion of the invention between the break lines forms no part of the claim.
